United States Patent Office

Des. 213,420
Patented Mar. 4, 1969

213,420

DIAPER FASTENER

Robert L. Fleming, 260 E. 262nd St.,
Euclid, Ohio 44132

Filed Feb. 9, 1968, Ser. No. 10,520

Term of patent 14 years

U.S. Cl. D2—448
Int. Cl. D2—08

FIG. 3

FIG. 1

FIG. 4

FIG. 2

FIG. 5

FIG. 8

FIG. 6

FIG. 9

FIG. 7

FIG. 10

FIG. 1 is a top elevational view of the diaper fastener of this invention.

FIG. 2 is a bottom elevational view of the diaper fastener of this invention.

FIG. 3 is a left end elevational view of the diaper fastener of this invention.

FIG. 4 is a right end elevational view of the diaper fastener of this invention.

FIG. 5 is a cross-sectional view taken along the line 5—5 of FIG. 1.

FIG. 6 is a top elevational view of a second embodiment of the design for a diaper fastener as shown in FIG. 1 and wherein the left end of the diaper fastener of FIG. 1 has been flattened and the right end has been shortened.

FIG. 7 is a bottom elevational view of the second embodiment of the diaper fastener of this invention.

FIG. 8 is a left end elevational view of the second embodiment of the diaper fastener of this invention.

FIG. 9 is a right end elevational view of the second embodiment of the diaper fastener of this invention.

FIG. 10 is a cross-sectional view taken along the line 10—10 of FIG. 6.

I claim:

The ornamental design for a diaper fastener, as shown.
